SWITCHING SYSTEM

Aloysius J. Busch, Madison, N. J., assignor to Bell Telephone Laboratories, Incorporated, New York, N. Y., a corporation of New York

Application December 12, 1940, Serial No. 369,705

8 Claims. (Cl. 179—18)

This invention relates to automatic switching telephone systems and particularly systems of this character having selectable devices for controlling switching connections.

The object of the invention is to provide an improved and economically arranged link switching system for automatically establishing switching connections for telephone calls in a minimum time period.

Heretofore link switching systems have been provided for selecting senders and other devices which are automatically responsive to a signal transmitted by an incoming or an outgoing trunk circuit. Systems of this kind have been shown in the patent application of G. V. King, J. B. McKim and O. Myers filed September 15, 1939, Serial No. 295,010, issued as patent 2,236,246, March 25, 1941, and patent application of A. J. Busch and F. J. Scudder filed September 15, 1939, Serial No. 295,012. Such systems provide senders or other devices available to a link switching system for selection by said link switching system when found idle and for connection to a trunk circuit through the contacts of a link switch. These systems, however, make a test of the available senders in a group and if all of the senders are busy, the link switching system is disconnected from the trunk circuit.

A feature of the present invention is a link switching system having devices for simultaneously connecting the senders of a first group of senders with sender testing facilities in search of an idle sender and when the senders tested in this group are found busy, said testing facilities are successively switched to the senders in a plurality of different groups under the control of sender testing facility switching devices and a timing device; the senders of each group being simultaneously tested by said testing facilities during the progression of said testing facilities from one group of senders to another.

Another and related feature resides in arresting the operation of the testing facility switching devices when an idle sender is selected from any of said plurality of groups.

Another and related feature resides in a link switching system according to the first feature comprising a plurality of link switches and a plurality of link control circuits each having said sender testing facilities switching devices and a timing device therein and each having a plurality of different groups of senders available thereto for test, with means for selecting an idle link control circuit responsive to the actuation of a trunk start circuit, said selected control cir-

cuit having means to make said successive test of different sender groups and disconnect itself from said trunk after a plurality of groups of senders have been repeatedly tested for a predetermined time period and no idle sender has been found, and for arranging the link switching system so that another idle link control circuit may be selected for testing another plurality of groups of senders to find an idle sender.

Another and related feature resides in a link switching system according to the first feature comprising a plurality of link control circuits each having available thereto different characters of senders for selection; a plurality of groups of each different character of senders being available to each control circuit and each control circuit having means therein responsive to a signal from a trunk circuit for determining the character of sender groups from which an idle sender shall be selected.

These and other features will be discussed more fully in the following description.

To illustrate the features of the invention reference may be had to the accompanying drawings in which Fig. 1 and Fig. 2 illustrate a trunk circuit diagrammatically and a link switching system comprising link switches, selectable link control circuits, a link connector, link frame relays and sender groups.

General description

The general organization of circuits and equipment for use with a link switching system according to the present invention may be of the character fully disclosed in patent application Serial No. 295,012, filed by A. J. Busch and F. J. Scudder September 15, 1939, and may be cooperatively associated with a cross-bar switching system of the character disclosed in patent application Serial No. 295,010, filed by G. V. King, J. B. McKim and O. Myers, September 15, 1939 issued as Patent 2,236,246 March 25, 1941.

In the foregoing systems a call from a toll office energizes the apparatus of an incoming intertoll trunk circuit which causes the selection of a link connector and link control circuit. The link control circuit selects an idle incoming sender and actuates a primary link switch and a secondary link switch for associating the incoming sender so selected with the calling incoming trunk through the contacts of these primary and secondary link switches. The incoming sender is set by impulses transmitted from the distant toll office. These impulses may be used for setting the code registers of the in-

coming sender and where necessary for setting both the code and numerical registers of this sender. The energization of the incoming sender associates a marker therewith and causes the transfer of the code registers from the sender to this marker. In response to the energization of the code registering equipment in the marker other equipment is operated for causing the selection of an idle outgoing trunk to the desired distant office. The marker selects an idle outgoing trunk and causes the energization of switches for connecting the incoming and outgoing trunks together. For calls requiring the transmission of numerical digits an outgoing sender is selected by the outgoing trunk circuit after a signal is transmitted to the outgoing trunk for this selection. To obtain the services of an outgoing sender the outgoing trunk also energizes a link connector and link control circuit causing the selection of an idle outgoing sender from a large plurality of senders, which, after it is selected, is connected through primary and secondary switches of the link circuit to the outgoing trunk. The numerical digits are transferred from the incoming sender through the contacts of the secondary and primary link switches first selected by the incoming trunk, through the incoming trunk circuit, thence over cross-bar switches to the outgoing trunk circuit, thence over the contacts of the primary and secondary link switches selected by the outgoing trunk, to the registers of the selected outgoing sender. The numerical registrations received by the outgoing sender are transmitted to a distant office over the contacts of the secondary and primary switches associated with the outgoing sender and over the outgoing trunk conductors to the distant office.

The trunk circuit 100 diagrammatically illustrated in Fig. 1 of the present embodiment may be considered as either an incoming or outgoing trunk of the same character as the intertoll trunk illustrated in Figs. 1 and 7 of the aforementioned patent application filed by A. J. Busch and F. J. Scudder. This trunk may be used either as a trunk incoming from the distant office or an outgoing trunk for connecting calls from this office to a distant office. The energization of this trunk when used as an incoming trunk establishes a start circuit which governs the selection of an idle link connector and a link control circuit for associating an incoming sender and marker with the incoming trunk.

The type of equipment to be selected is governed by the intertoll trunk circuit. For example, when the two-way intertoll trunk circuit is used as an incoming intertoll trunk, a class signal is transmitted to the control circuit indicating that an idle incoming sender is required. The control circuit is then associated with a plurality of incoming senders which are also connected to certain levels of the secondary cross-bar link switches. Each control circuit may be connected to a different plurality of senders, some of which are the same as those connected to other control circuits. Assuming that there are one hundred and fifty incoming senders and ten control circuits, the one hundred and fifty senders are divided among the control circuits in any manner desired. An example may be assumed in which ten senders may be simultaneously tested by the control circuit, which ten senders are connected to ten different levels of a plurality of secondary link switches. An arrangement is provided, however, to prevent the test of

senders which are connected to busy secondary link switches. This busy condition is indicated by a ground connected to the hold magnet of link switches associated with busy senders. When an idle sender is chosen from a group of senders the select magnet of the proper link switch level is operated and the hold magnets of the proper verticals in both the primary link switch and the secondary link switch are operated. The incoming intertoll trunk is thus connected through the primary and secondary link switches to the idle incoming sender selected. A signal is transmitted to the distant calling operator that pulses may now be transmitted for setting the registers of the sender. During this period the apparatus of the incoming sender is energized for selecting an idle marker. This is accomplished through the energization of a marker connector in the manner fully described in Patent 2,236,246 to King-McKim-Myers, filed September 15, 1939 and issued March 25, 1941.

When the telephone connection requires the transmission of numerical pulses the outgoing trunk energizes a link start circuit for establishing connection with a link switching system for selecting a link control circuit for obtaining the services of an outgoing sender. When the link control circuit is associated with the outgoing trunk a distinctive class signal circuit is established from the outgoing trunk circuit to the link control circuit which causes the link control circuit to test a plurality of outgoing senders in order to find an idle sender. The outgoing senders tested are associated with a particular plurality of levels of the secondary link switches. When an idle outgoing sender is found, the proper select magnets and hold magnets of the primary link switch and the secondary link switch are operated. This associates an outgoing sender with the outgoing trunk over link switch contacts and since the incoming trunk is connected to an incoming sender over other link switch contacts, circuits may be completed at this time for connecting the incoming sender to the outgoing sender through the incoming trunk, cross-bar switches and an outgoing trunk. A signal is given from the outgoing sender to the incoming sender and the numerical pulses are transmitted from the incoming sender for setting the registers of the outgoing sender. This ordinarily completes the services of the incoming sender and at this time this sender may be released, which releases the hold magnets of the link switches which associated the incoming sender with the incoming trunk.

The present invention contemplates the foregoing arrangement of link switches and in addition contemplates control circuit devices for selecting an idle sender in a minimum time period for telephone connections during heavy load intervals by successively and repeatedly connecting link control circuit testing facilities with a plurality of different groups of senders under the control of testing facility switching devices and a timing device when all of the individual senders in the groups tested are busy. A plurality of different groups of senders are thus made available to the link control circuit testing facilities each group having a large plurality of senders therein. The senders of each group are simultaneously tested and consequently the rapid transfer of testing facilities in the control circuit successively and repeatedly from one group to another to find an idle sender has the advantage of satisfying the requirements for completing a telephone call in

the shortest possible time. The sender in the different groups may be cross-connected in a manner to be available to the testing facilities of a plurality of link control circuits and when so connected are arranged in a different order with relation to the testing facilities of the different control circuits so that the first order of senders tested by one control circuit may be the second or third order of senders tested by another control circuit. This makes available a large plurality of senders to the testing facilities of each control circuit with a minimum amount of equipment.

The testing facilities of the link control circuit are first connected to the senders of one group and if an idle sender is found in this group it is taken for use and the control circuit testing facilities are not associated with another group of senders. When the senders of the first group are all found busy, the link control circuit testing facilities are automatically transferred to the senders of another group which are simultaneously tested by the testing facilities in an effort to find an available idle sender. When the senders of the latter group are all found busy a transfer is made to another group of senders or to the first group of senders tested to repeat the test of these senders in an effort to find an idle sender which may have been released by another telephone connection. This automatic transfer of the testing facilities continues from one group of senders to another for a period of time until an idle sender is found or this period of time expires. The action of the testing facility switching devices is automatically arrested when an idle sender is found in any sender group. If no idle sender is found in the allotted period of time the link control circuit is disconnected from the trunk circuit and the trunk is automatically associated with another control circuit which makes a progressive test of the groups of senders associated therewith. This continues as long as a sender is demanded by a trunk circuit.

Fundamentally, the arrangement is as follows: Circuits are established by trunk circuit equipment for selecting a link control circuit and for operating a class relay combination for directing the control circuit to select a particular character of equipment. In this instance, groups of senders have been illustrated as selectable equipment. Two groups of incoming senders and two groups of outgoing senders are shown, each group having a plurality of senders therein. The class signal, therefore, directs the control circuit to select a sender either from a group of incoming senders or a sender from a group of outgoing senders. Before the class signal may be effective a control circuit is selected and associated with the trunk circuit. A multicontact relay and a connector are used for associating the selecting control circuit with the trunk circuit and with relays which are selectively operated for associating a particular group of senders with the control circuit. After the class relay combination is energized, other equipment in the control circuit associates testing facilities with a group of senders of the character directed by the trunk circuit for simultaneously testing the senders in this group. The testing facilities are shown in the right portion of Fig. 1 and constitute relays 130 to 137 which are associated with the senders of a group and with the link switches which are connected to the same senders. Relays 138, 139, 140 and 141 cooperate with relays

130 to 137, certain of which are energized when an idle sender is selected. Relays, such as 130, 131, 132 and 133, are associated with different link switch combinations, each combination comprising a vertical on a primary link switch and a vertical on a secondary link switch, each vertical being associated with a plurality of horizontal levels on these switches. The hold magnet of one vertical on the primary link switch and the hold magnet of one vertical on a secondary link switch are connected in multiple and may be known as a switch combination. These hold magnets are simultaneously energized when a sender connected to a horizontal level of the switch is selected. Ground is associated with the hold magnet for its operation and therefore when any of the relays 130, 131, 132 and 133 are associated with a busy switch combination, the relay is operated. This disassociates the windings of testing facility relays 134, 135, 136 or 137 from the senders connected to the busy link switch combination. There are as many relays, such as 134-135, as there are senders in an outgoing sender group and as many relays, such as 136-137, as senders in an incoming sender group. Relays 134 and 135, therefore, represent a plurality of relays which may be associated with senders of one group of a particular character. Relays 136 and 137 represent another plurality of relays which may be associated with a sender group having senders of a different character. The class relays 202 and 203 determine which of the relays shall be associated with the groups of senders to be tested.

Upon the actuation of the control circuit the testing facilities are chosen and associated with the senders of a group. A testing facility switching combination is also energized which allows the testing facilities such as relays 132, 133, 136 and 137 to be associated with the senders of this group for a limited period of time which is of sufficient duration to determine whether there is an idle sender in the group. These testing facility relays 132, 133, 136 and 137 are then automatically transferred to the senders of another group of the same character if an idle sender was not found in the first group tested. When no idle sender is found in the second group tested the sender facility testing equipment is either transferred to another group of senders of the same character or returned to the first group of senders to repeat the test of senders in this group. Between the original test of the first group of senders and the second test of the senders in this group, it is probable that one of the senders has been released by a telephone connection which has been completed. However, if no idle sender is found the testing facility switching arrangement continues to function for transferring the testing facilities from one group of senders to another for a time period controlled by timing devices comprising interrupter 225, relay 214 and relays 216 to 219, inclusive. The latter relays are energized under the control of interrupter 225 to determine the period of time for switching the link control testing facilities for successively testing the senders of a plurality of sender groups and repeating the test of senders in these groups if necessary.

When during the foregoing regulated time period no idle sender is found, a second function of the time circuit is to cause the release of the link control circuit. This, however, does not release the entire link switching system. The link control circuit is restored to normal and in

so doing disconnects the trunk circuit from this link control circuit but arranges the equipment of the link switching system so that another link control circuit is immediately selected. The second link control circuit functions in the same manner since it has the same testing facilities and the same testing facility switching equipment and timing circuit. The second control circuit, however, has available different groups of senders than are available to the first link control circuit selected.

When an idle sender is found, ground is associated with a lead extending to the link control circuit and operates a testing facility relay such as 134, 135, 136 or 137. This relay energizes other relays in the control circuit for arresting the operation of the testing facility switching mechanism and for associating ground with the hold magnet of the link switch vertical with which the idle sender is connected, as shown in the aforementioned patent application of A. J. Busch and F. J. Scudder. Circuits are established when an idle sender is selected to indicate to the control circuit with which horizontal level of the link switches the idle sender is connected. The control circuit has equipment therein for energizing the select magnets associated with these levels. This equipment may be the same as in the aforementioned patent application and is not shown herein. In this manner a particular idle sender is chosen from a large plurality of senders and the associated link switch is energized by the control circuit for connecting the selected idle sender with the trunk circuit which caused the selection of the control circuit.

Detailed description

A trunk circuit which requires the services of a link and link control circuit either in response to an incoming call or in response to an outgoing connection energizes a link start circuit and a class indicating circuit by the operation of relays in the trunk circuit. The start circuit for engaging the services of a link and link control circuit may be traced from ground 102 in the trunk circuit 100, contact of relay 150, winding of start relay 127 to battery. The energization of the start relay actuates a sequence circuit in connector 129, diagrammatically shown, for selecting an idle control circuit in a group including a plurality of such control circuits. This sequence circuit and connector 129 may be of the character shown in detail in the aforementioned application of A. J. Busch and F. J. Scudder. Each control circuit has a representative relay in each connector so that any one of the control circuits may be associated when idle with any of a large plurality of trunks in any of a plurality of trunk groups. The sequence circuit and connector are energized by battery through resistance 151, contact 4 of relay 127 to the sequence circuit relays of connector 129. Ground is extended from contact 2 of relay 127 through the sequence circuit shown in dotted lines, winding of relay 128 to battery operating the multicontact relay 128. Assuming that the control circuit shown in Fig. 2 and the right portion of Fig. 1 is the idle control circuit selected, a circuit is immediately established for energizing the off-normal relay 215 from battery, through its winding, contact 1 of relay 222 to ground on contact 1 of relay 128. A circuit is also established for a trunk group relay such as relay 226 from ground on contact 1 of relay 127, through contact 12 of relay 128, winding of relay 226 to bat-

tery. Each start relay, such as 127, is associated with a particular group of trunks. The control circuit is equipped with trunk group relays such as relay 226, equivalent in number to the number of trunk groups served by a link group combination. For example, if there are ten trunks in a group and the link is arranged to serve ten such groups of trunks, there would be one hundred trunks in the group which would be represented by ten trunk group relays 226 in the control circuit. The operation of the off-normal relay 215 operates the associated trunk group relay 126 in the link frame circuit through the contact of a particular trunk group relay 226 in the link control circuit. The operation of relay 126 associates the control circuit with a plurality of sender group relays and also establishes a local circuit for the operation of relay 150. This circuit may be traced from ground, through contact 5 of relay 126, contact 15 of relay 128, winding of relay 150 to battery. A locking circuit is also established through contact 5 of relay 126 for the start relay 127. Relay 150 opens the original energizing circuit for the start relay 127 and this relay remains operated over its locking circuit until the release of relay 126.

The trunk circuit 100 indicates to the sender whether it requires the services of an incoming sender or an outgoing sender or other devices which may be selected by a control circuit of this character. A trunk circuit requiring the services of an incoming sender operates a trunk circuit relay to establish a circuit from ground through resistance 103, contact 14 of relay 128, winding of relay 203 to battery operating relay 203. A trunk circuit requiring the services of an outgoing sender operates a trunk circuit relay for establishing a circuit from ground through resistance 101, contact 13 of relay 128, winding of relay 202 operating the latter relay. These are known as class relays to indicate to the link control circuit the character of equipment to be selected. Assuming the services of an incoming sender are required, relay 203 is energized which establishes a circuit from battery, through resistance 228, contact 1 of relay 204, contact 2 of relay 203, contact 2 of relay 202 to the contacts of transfer relays 200 and 201. This circuit is prepared in advance of the operation of either relay 200 or 201. Relays 207 and 209 control the successive operation of relays 200 and 201.

Selecting an idle sender in first group tested

A number of relays are simultaneously energized at the time that the control circuit off-normal relay 215 is operated which immediately associates the testing facilities of the control circuit with a group of senders, and initiates the control of switching relays and a timing circuit. The timing device is energized by the operation of relay 214 from battery, through its winding, contact 2 of relay 215 to ground on contact 2 of relay 222. The operation of this timing device will be described later. Relay 210 is energized over a circuit from ground on contact 3 of relay 215, contact 1 of relay 211 to relay 210 to battery. The latter relay is a slow-release relay which functions in combination with relay 211 for transferring the testing facilities from one group of senders to another when all senders in a tested group are found busy. The operation of relay 210 connects ground through its contact 1, continuity contact of relay 209, winding of relay 209, resistance 251 to battery energizing relay 209. The energization of this relay inherently assumes

that relay 207 is normal and consequently a circuit is established for relay 209. This circuit may be traced from battery, through resistance 208, contact 1 of relay 207, winding of relay 200, contact 3 of relay 210, contact 1 of relay 205 to ground through contact 3 of relay 201. The operation of relay 209 establishes a circuit for connecting the senders of a group with the control circuit testing facilities shown in the right portion of Fig. 1 by energizing one of the relays 122 or 123 depending upon the character of sender wanted for the telephone connection. Since in the example being given relay 200 and class relay 203 are energized, a circuit for relay 122 is established over a circuit traced from battery, through resistance 228, contact 1 of relay 204, contact 2 of class relay 203 operated, contact 2 of class relay 202 normal, contact 1 of relay 200, conductor 234, contact 5 of relay 128, contact 4 of relay 126, winding of relay 122 to ground, energizing the latter relay. Relay 122 establishes a circuit for operating relay 205 for initiating the operation of the testing facility switching mechanism as explained later. Ten incoming senders have been shown as sender group 110 which are associated over ten leads 114-115 through ten contacts of relay 122 shown as contacts 1 and 2, thence over leads 160 and 161, through the contacts 1 and 3 of relay 128, connector 129, contact 2 of relay 133, winding of relay 137 to battery, and contact 2 of relay 132, winding of relay 136 to battery. Assuming that there are ten senders in a group, there would also be ten relays such as 136 and 137. When a sender is idle, ground is associated with the leads traced. Assuming that the tenth sender is idle, ground would therefore be associated from the sender through contact 2 of relay 122, lead 161, contact 3 of relay 128, contact 2 of relay 132, winding of relay 136 to battery which would operate relay 136. This relay establishes a locking circuit for itself through its contact 2 to the operating ground in the sender. The leads from the sender are carried through the contacts of relays such as 132 and 133 to prevent a test of senders which are connected with busy link switches. A busy link switch has ground connected with the hold magnet for operating this magnet. This ground establishes a circuit for the relays such as 132 opening the leads extending to relays such as 136.

It has been assumed that an idle sender has been found in the first group of senders tested which causes the operation of relay 136. This relay establishes a circuit for relay 140 from ground connected to the armature and contact 4 of relay 136, winding of relay 140 to battery. Relay 140 opens the circuit for relay 211 to arrest the action of the testing facilities switching devices as described later. Ground is also connected through contact 3 of relay 136, winding of relay 141 to battery to operate the latter relay. The operation of relay 141 establishes an obvious circuit for operating relay 138 and also establishes obvious circuits for operating relays 130, 131, 132 and 133. The operation of the latter relays open all testing leads to the senders and relays such as 136 and 137 must then be maintained on their locking circuits. Since the tenth sender was selected as idle this indicates that the first nine senders were busy and consequently when the test was made and relays 132 and 133 energized, relay 136 is the only relay to remain energized on its locking circuit. With relay 138 energized a circuit is established from

ground on contact 1 of relay 137, over a chain circuit through intermediate relays, contact 1 of relay 136, contact 3 of relay 138, winding of hold magnet 105 to battery which operates this hold magnet to lock cross-bar switch contacts of a horizontal level connected to the selected sender. If, however, relay 137 had been operated indicating that the first sender is idle, there could have been other relays such as 137 and 136 associated with idle senders which would also have operated and established their locking circuits. The first idle sender, however, is the one selected since a chain circuit prevents the selection of more than one sender. This is clear from observing that ground connected with the armature 1 of relay 137 is disassociated from all other relays when relay 137 is operated and is extended through contact 4 of relay 138 for energizing the link switch hold magnet 105. Since this ground is disassociated from other relays none of the other link switch hold magnets may be operated. The operation of relay 140 prevents the control circuit from making further tests as will be later described. As explained in the aforementioned patent application to A. J. Busch and F. J. Scudder after a sender is seized a second test of this sender is made to satisfy the control circuit that it is free for use. This testing circuit is diagrammatically shown as test circuit 206 which may operate in the same manner as described in the above application. When the test is satisfactory, a circuit is established through the test relay contact for energizing test cut-off relay 204 which operates relay 212 from ground through its contact 5, winding of relay 212 to battery. Relay 212 energizes relay 222 for causing the release of the control circuit. The operation of relay 222 opens the circuit for the timing relay 214 and the off-normal relay 215 causing their release. The release of relay 214 causes the timing relays 216, 217, 218 and 219 to restore to normal. The release of relay 215 opens the circuit for the progressive testing relay 210 through its contact 3 and through its contact 1, opens the circuit for relay 126 causing the release of the latter relay. The release of relay 126 opens the holding circuit for start relay 127 which causes the release of trunk group relay 226 and the release of link relay 128. Relay 150 is slow in releasing so that the trunk start circuit is opened to insure the release of relay 128.

Progressive and repeated test of sender groups

The foregoing gives the circuits established for testing one group of senders when an idle sender is found in this group. In presenting the arrangements of the invention, four groups of senders have been shown, two groups of incoming senders 110 and 112 and two groups of outgoing senders 111 and 113. Relay 122 is operated for associating the testing facilities including relays 136-137 with the first group of incoming senders and relay 124 is operated for associating these testing facilities of the control circuit with the second group of incoming senders. Relay 123 is operated for associating the testing facilities of the link control circuit including relays 134-135 with the first group of outgoing senders and relay 125 is operated for associating these testing facilities with the second group of outgoing senders. When all of the senders of a group are found busy, the switching equipment of the link control circuit operates in the following manner: Relays 287 and 209 successively energize relays 208 and 201 for switching from

one group of senders to another. Relays 210 and 211 control the operation of relays 207 and 209. Relays 210 and 211 are progressively energized under the control of the testing facilities as they are associated with the sender groups. As previously described relay 210 is energized from ground on contact 3 of the off-normal relay 215 and in turn energizes relay 209 which locks to ground on its continuity contact. Relay 207 is normal since a ground shunt is connected to the lower terminal of its winding through contact 1 of relay 210. The senders of the sender group 110 are tested as previously described. The operation of relay 122 for testing the senders of sender group 110 associates ground the winding of relay 205 operating the latter relay. A circuit is thus established for relay 211 from battery, through its winding, contact 2 of relay 204, contact 3 of relay 205, contact 1 of relay 140, contact 1 of relay 139 to ground. Relay 211 is a slow operating relay and does not have time to operate if an idle sender exists in sender group 110 because when an idle sender is found in this group, a circuit is established for relay 140 which opens the circuit for relay 211. Relay 139 is associated with the outgoing sender testing facilities for this same purpose. Assuming that neither relays 140 nor 139 are energized and relay 211 thus has time to energize, a transfer from one group of senders to another is made in the following manner: The energization of relay 211 opens a circuit for relay 210 causing its release. The release of relay 210 removes the shunt from the winding of relay 207 and thus causes the operation of relay 207 from battery through resistance 250, winding of relay 207, contact of relay 209 to ground. The energization of relay 207 opens the circuit for relay 200 and prepares a circuit for relay 201 from battery through resistance 208, contact 2 of relay 207, winding of relay 201 to contact 2 of relay 210. Relay 210 must, however, again operate before this circuit is completed. The release of relay 200 opens the energizing circuit for relay 122 causing its release. The release of relay 122 opens the energizing circuit for relay 205 which causes its release. The release of relay 205 opens the energizing circuit for relay 211 and the release of relay 211 energizes relay 210. Relay 210 now completes the circuit for relay 201 through its contact 2, contact 2 of relay 205 to ground on contact 3 of relay 200 which was released. At this time relay 210 also establishes a circuit for causing the release of relay 209 by shunt. Ground from contact 1 of relay 210 is connected through the inner contact 3 of relay 207 to a point between resistance 251 and the winding of relay 209. Since this places ground on both terminals of the winding of relay 209, the relay releases and relay 207 remains operated through the continuity contact of relay 209, winding of relay 207, resistance 250 to battery.

With relays 207 and 201 operated a circuit is established to operate the link frame relay 124 for associating the control circuit testing facilities with a second group of incoming senders. A circuit for relay 124 may be traced from ground, through its winding, contact 2 of relay 126, contact 3 of relay 128, conductor 232, contact 1 of relay 201, contact 2 of relay 202, contact 2 of relay 203, contact 1 of relay 204, resistance 228 to battery. It will be remembered that class relay 203 was operated for associating incoming senders with the control circuit and relay 202 is normal. The operation of relay 124

connects ten test leads designated 118 to 119 from the senders in group 112 through contacts 1 and 2 of relay 124 which represent ten contacts thence through contacts 7 and 8 of relay 128, connector 129, contact 2 of relay 133, winding of relay 137 to battery and contact 2 of relay 132, winding of relay 136 to battery. As will be remembered ten relays such as 136 and 137 are used for testing ten senders in a group. If the first sender of a group is idle and thus has ground associated with conductor 118 relay 131 is operated and the search for an idle sender is discontinued by the operation of relays 140, 141 and 138 as previously described. If, however, all of the senders in group 112 are busy, none of the ten relays 136 to 137 will be operated and the testing of senders in other groups will continue. The operation of relay 124 for associating the testing facilities of the link control circuit with the sender group 112 also associates ground through its contact 3, contact 1 of relay 128, through connector 129, conductor 236, winding of relay 205 to battery for operating relay 205. Whenever the testing facilities of the control circuit are associated with the senders of any group relay 205 is operated. The operation of relay 205 initiates the transfer of the testing facilities to another group by energizing relay 211 over a circuit which may be traced from battery, through its winding, contact 2 of relay 204, contact 3 of relay 205, contact 1 of relay 140, contact 1 of relay 139 to ground. As previously shown, relay 140 and, as will be shown, relay 139 are normal when all of the senders of a group are busy and are energized immediately when an idle sender is found in a group. The operation of relay 211 again releases relay 210 which causes the release of relay 207 since relay 209 was previously released. The release of relay 207 opens the circuit for relay 201 which was locked to ground through its contact 3. Since the circuit for relay 200 is now open at contact 3 of relay 210 a test of another group of senders cannot be made until relay 210 again operates. Upon the release of relay 201, the following takes place: Relay 201 opens the energizing circuit for relay 124; the release of relay 124 opens the energizing circuit for relay 205; the release of relay 205 opens the energizing circuit for relay 211 and the release of relay 211 again establishes the energizing circuit for relay 210. With relay 210 energized, a circuit is again established for relay 200 or a similar relay if more than two groups of senders are provided. This circuit may be traced from battery, through resistance 208, contact 1 of relay 207, winding of relay 200, contact 3 of relay 210, contact 1 of relay 205, contact 3 of relay 201 to ground. The operation of relay 200 again energizes relay 122 as previously traced from ground, through its winding, contact 4 of relay 126, contact 5 of relay 128, through connector 129, conductor 234, contact 1 of relay 200, contact 2 of relay 202, contact 2 of relay 203, contact 1 of relay 204, resistance 228 to battery. The testing facilities of the link control circuit including the ten relays 136 to 137 are again associated with the ten senders in sender group 110. Between the time that the senders of this group were originally tested and the second test after the senders of group 112 were tested, it is usual that a sender will have been released in group 110 and consequently an idle sender will be found. The link control circuit switching apparatus continues to function so that if an idle sender is not found in the sender group 110, the

testing facilities will again be switched to the sender group 112. For this purpose the operation of relay 210 again energizes relay 209 from ground through contact 1 of relay 210, continuity contact of relay 209, winding of relay 209, resistance 251 to battery. This prepares a circuit for the operation of relay 207 when relay 210 again is released.

Timing devices

The transfer of the testing facilities of the link control circuit continues as described above for a period of time which is regulated by the timing relays and interrupter shown in the lower portion of Fig. 2. At the end of the time interval regulated by these relays, if an idle sender has not been selected, the link control circuit is released and disassociated from the trunk actuating circuit in the following manner: When the link control circuit was seized by a trunk circuit, relay 215 was operated which energized relay 214 as previously stated. This associates ground from contact 1 of relay 214 with the movable member 3 of interrupter 225 which alternately closes its contacts 1 and 2 in measured time intervals regulated by the interrupter cam 4. The first closure of contact 1 energizes relay 216 from ground, through contact 1 of relay 214, contact 1 of interrupter 225, contact 5 of relay 218, contact 1 of relay 219, winding of relay 216 to battery. Relay 216 locks over a circuit from battery through its winding and its contact 2, contact 1 of relay 217 to ground on contact 3 of relay 214. When interrupter 225 associates its member 3 with contact 2, ground is connected from contact 1 of relay 214 through contact 2 of the interrupter, contact 3 of relay 216, contact 4 of relay 218, winding of relay 219 to battery operating relay 219. This relay locks through its contact 2 to ground on contact 2 of relay 214. The second association of the member 3 with its contact 1 energizes relay 217 from ground on contact 1 of relay 214, contact 1 of interrupter 225, contact 5 of relay 218, contact 1 of relay 219, winding of relay 217 to battery. Relay 217 is locked through its contact 1 to ground on contact 3 of relay 214. The operation of relay 217 releases relay 216 since relay 216 was held operated through contact 1 of relay 217 and since the original operating circuit for relay 216 was carried through contact 1 of relay 219. The second association of member 3 of interrupter 225 with contact 2 energizes relay 218 from ground on contact 1 of relay 214, contact 2 of interrupter 225, contact 3 of relay 216, contact 2 of relay 217, winding of relay 218 to battery. This completes a time interval in which the testing facilities of the control circuit may be associated with a number of groups of senders in an effort to find an idle sender for completing a telephone connection. If no idle sender has been found during this interval, the control circuit selected is now disassociated from the trunk but the link switching system remains associated with this trunk. This condition is recognized by the timing circuit devices when the interrupter again associated its member 3 with its contact 1. The release of the control circuit is made when a group of senders is being tested and no idle sender is found in this group. Consequently, relay 205 is operated and relays 139 and 140 are normal. Under the several conditions outlined above a circuit is again established for relay 216 from ground through contact 1 of relay 214, contact 1 of the interrupter, contact 5 of relay 218 which was the last timing relay to be oper-

ated, winding of relay 216 to battery. Relay 216 now closes a locking circuit for itself through its contact 2, contact 1 of relay 218, to ground on contact 3 of relay 214 and establishes an operating circuit for relay 212. This circuit may be traced from battery, through the winding of relay 212, contact 2 of relay 211, contact 1 of relay 216, contact 2 of relay 218, contact 2 of relay 139, contact 4 of relay 204, contact 2 of relay 140, contacts 1 or 2 of relay 205 to ground either on contact 3 of relay 200 or contact 3 of relay 201. It will be noted that the foregoing conditions for establishing the circuit for relay 212, i. e., with relay 205 operated and relays 139 and 140 normal is the same condition which prevails for energizing relay 211. It will also be noted that the circuit for relay 212 was carried through contact 2 of relay 211. Relay 211 is slow-to-operate and consequently a circuit is established for relay 212 after the second operation of relay 216 before the slow-to-operate relay 211 has time to operate.

Release of link control circuit

The operation of relay 212 associates ground with control circuit release relay 222 operating relay 222 which opens the circuits for relays 215 and 214 causing their release. The release of relay 214 restores the timing relays 216, 217, 218 and 219 to normal. Relay 222 remains locked through ground on contact 1 of relay 128 and does not release until the link control equipment has all been released. The release of relay 215 disassociates ground from the operating circuit for trunk group relay 126 and also disassociates ground from the switching relay 210 to prevent further functioning of this relay combination. The release of relay 126 opens the holding circuit for the start relay 127 and opens the circuit for the slow-to-release relay 150. The release of the start circuit 127 opens the circuit for the sequence relays in the connector 129 which releases and opens the circuit for the multicontact relay 128. The equipment of the link control circuit is thus entirely released and the connector and trunk start circuit lead is momentarily disassociated from the link switching system by the continued operation of the slow-to-release relay 150. After a short time interval, relay 150 releases again establishing the start circuit from the trunk circuit 100. If at this time the trunk circuit still requires the services of a link control circuit for obtaining an idle sender the start circuit continues to be energized in the trunk circuit and again causes the operation of the start relay 127. This energizes the sequence circuit in connector 129 causing the selection of another link control circuit. The second link control circuit taken for use functions in the same manner as the link control circuit herein described but has access to different senders in the groups of senders associated with this second control circuit and an idle sender is ordinarily found by this second control circuit even during the heaviest telephone call load periods and, consequently, with this arrangement an idle sender is usually found in a period not to exceed ten to fifteen seconds.

For the following description, the trunk circuit 100 may be assumed as either a two-way trunk circuit combining the functions of an incoming and an outgoing trunk or a one-way outgoing trunk circuit. In either case the outgoing trunk requiring the services of an outgoing sender energizes a start circuit 102 by the energization of a

relay in the trunk circuit which associates ground through the contact of relay 150, winding of start relay 127 to battery operating the link start relay. This outgoing trunk also associates ground through resistance 101 for transmitting a signal to a link control circuit after it has been selected. The energization of the start relay 127 selects a link control circuit in the manner previously described and energizes relay 128 for associating the trunk circuit with the selected link control circuit and for associating the control circuit testing facilities with the contacts of the link frame relays 123 and 125. The off-normal relay 215 is energized from ground on contact 1 of relay 128 and a trunk group relay such as 226 is energized from ground on contact 1 of the start relay. As previously stated this start relay is associated with a particular group of trunks and may or may not be the same start relay used for the selection of incoming senders. The trunk group relay 226 will probably be a different trunk group relay than the one used for the selection of incoming senders. After the operation of a trunk group relay such as 226 and the off-normal relay 215, a circuit is established for relay 126 which connects the windings of the link frame relays with the control apparatus of the link control circuit. At this time the class relay is operated by the trunk signal for indicating to the link control circuit the character of equipment such as outgoing senders to be selected. Relay 202 has been shown for this purpose and a circuit is established from battery through its winding, conductor 231, through connector 129, contact 13 of relay 128, trunk resistance 101 to ground. Relay 215 connects ground from its contact 3 through contact 1 of relay 211, winding of relay 210 to battery for energizing relay 210. Assuming that relay 207 is normal, the energization of relay 210 causes the operation of relay 209 in the manner previously described. A circuit for relay 200 is established from battery through resistance 208, contact 1 of relay 207, winding of relay 200, contact 3 of relay 210, contact 1 of relay 205, contact 3 of relay 201 to ground. This establishes a circuit for associating the link control circuit testing facilities with the first group of outgoing senders by energizing relay 123. The circuit for energizing the latter relay may be traced from ground through the winding of relay 123, contact 3 of relay 126, contact 4 of relay 128, through connector 129, conductor 233, contact 2 of relay 200, contact 1 of relay 202 operated, contact 1 of relay 203 normal, contact 1 of relay 204, resistance 228 to battery. The operation of relay 123 associates the senders of outgoing sender group 111 through an equivalent number of conductors 116 to 117, an equivalent number of contacts such as 1 and 2 of relay 123, thence over conductors 162 and 163, contacts 9 and 10 of relay 128, through connector 129, contact 2 of relay 131, winding of relay 135 to battery and contact 2 of relay 130, winding of relay 134 to battery. The number of relays 134 and 135 is equivalent to the number of senders in group 111. The operation of relays such as 134 and 135 when an idle outgoing sender is connected thereto is the same as described for incoming sender testing facility relays 136 and 137. A ground in an idle outgoing sender indicates that the sender is idle and operates the relays 134-135 corresponding to the idle senders. The operation of any one of these relays establishes an obvious circuit for relay 139 to prevent the link control circuit from making further

search for an idle sender. The operated relay also energizes relay 141 which functions as before and energizes relay 138 for associating ground from an energized relay 134-135 whichever is 5 the first in the sequence of relays energized. For example, if relay 135 is associated with an idle sender, ground is connected through the contacts 1 of relays 136 to 137 which are normal, contact 1 of relay 135, contact 2 of relay 138, through connector 129, winding of link switch magnet 107 to battery which energizes this holding magnet the select magnet associated with a particular horizontal level having previously been operated. 10 15 When all outgoing senders in the sender group 111 are found busy, the link control circuit automatically progresses for associating the control circuit testing facilities with another group of outgoing senders. When relay 123 was operated 20 for associating the testing facilities of the control circuit with the sender group 111, a circuit for relay 205 was established in the manner previously traced. The operation of relay 205 establishes an energizing circuit for relay 211 from battery, through its winding, contact 2 of relay 204, contact 3 of relay 205, contact 1 of relay 140, and contact 1 of relay 139 to ground. It is apparent that relay 139 remains normal if no sender in the group is found idle. Relay 211 25 30 opens the operating circuit for relay 210 in the manner previously described which causes the operation of relay 207 by removal of a shunt around its winding. This shunt may be traced from the contact of relay 210 when operated, contact 3 of relay 207 normal to a point between resistance 250 and the winding of relay 207. Since relay 209 is operated, ground is associated through its contact with the upper terminal of the winding of relay 207. The release of relay 210 35 40 consequently establishes an operating circuit for relay 207 from ground through the continuity contact of relay 209, winding of relay 207, resistance 250 to battery. The operation of relay 207 opens the circuit for relay 200 which releases relay 123 and the release of relay 123 opens the circuit for relay 205 causing the release of relay 211. The release of relay 211 reenergizes relay 210 and a circuit is established for relay 201. The circuit of relay 201 may be traced from battery 45 50 through the resistance 208, contact 2 of relay 207, winding of relay 201, contact 2 of relay 210, contact 2 of relay 205 to ground on contact 3 of relay 200. The reoperation of relay 210 also places a shunt around the winding of relay 209 to cause its release in the manner previously described. Relay 207 remains operated to ground on contact 1 of relay 210. The operation of relay 201 now establishes a circuit for link frame relay 125 to associate the testing facilities of the link control circuit with the senders of sender group 55 60 65 70 75 113. A circuit for relay 125 may be traced from ground, through its winding contact 1 of relay 126, contact 2 of relay 128, through connector 129, conductor 231, contact 2 of relay 201, contact 1 of relay 202, contact 1 of relay 203, contact 1 of relay 204, resistance 228 to battery. The senders of outgoing sender group 113 are connected to the testing facility relays over conductors 120 and 121, contacts 1 and 2 of relay 125 which are equivalent to the number of senders in the sender group, thence over conductors 162 and 163, contacts 9 and 10 of relay 128, through connector 129, contact 2 of relay 131, winding of relay 135 to battery, contact 2 of relay 130, winding of relay 134 to battery. If an idle sender is

found in the second group, the link control circuit equipment is opened so that the sender is taken for use. If all of the senders in the second group tested are found busy, the control circuit equipment continues to transfer the control circuit testing facilities from one group to another until disconnected by the timing circuit relays as previously described. Also, as previously described, after the control circuit is disconnected from the outgoing trunk and the trunk continues to energize its link start circuit another control circuit may be taken for use to find an idle outgoing sender for completing the telephone call.

When an idle sender is found in the first group tested or in subsequent groups tested the testing circuit 206 is associated with the idle sender taken for use. If this testing circuit is satisfied the test relay is operated for energizing relay 204 which opens the control circuit equipment through its contacts as shown, places a ground on conductor 252 for maintaining relays 207 or 209 in the position taken and also connects a ground through the winding of relay 212 to battery for operating the latter relay. This establishes an obvious operating circuit for the control release relay 222 which releases the control circuit equipment in the manner previously described. Under this condition the seizure of an idle sender energizes the equipment of the sender which establishes a circuit through the link switch contacts to the trunk circuit for opening the link start circuit in the trunk. Consequently, when the link circuit equipment is released the start relay 127 will not be again operated as it is when all of the senders tested are found busy.

The timing circuit relays 216, 217, 218 and 219 are associated with a trouble alarm circuit if under certain conditions a fault exists in a link control circuit which prevents it from operating satisfactorily. The timing circuit relays operate in the same manner as previously described and it will be remembered that relay 216 was operated and then released when relay 218 was operated. Under the condition for releasing the link control circuit previously described, a circuit is established for relay 212 through contact 1 of relay 216, contact 2 of relay 218 and through other contacts of the link control circuit which must be in a particular position for the circuit to be established. When this release circuit is not established the interrupter 225 continues to function and when its member 3 reaches its contact 2 a circuit is established from ground through contact 1 of relay 214, member 3 and contact 2 of interrupter 225, contact 3 of relay 216, contact 4 of relay 218, winding of trouble relay 220 to battery. The energization of this trouble relay associates ground through its contact to a trouble alarm circuit which lights a lamp to indicate the link control circuit in trouble and also sounds an alarm which may be accomplished in any manner shown in trouble alarm circuits known in the art.

What is claimed is:

1. In a telephone system, trunks, a link switching system, a plurality of groups of trunk connecting devices available to said link switching system, each group comprising a plurality of trunk connecting devices, means in a trunk for actuating said link switching system, testing facilities in said link switching system arranged to simultaneously test the trunk connecting devices of a group, an automatically operable switching device for successively and repeatedly switching

said test facilities from one group of trunk connecting devices to another for successively and repeatedly testing the trunk connecting devices of said groups and for selecting an idle trunk connecting device in one of said groups, and means in said testing facilities for arresting the action of said switching device when an idle trunk connecting device is selected.

2. In a telephone system, trunks, a link switching system, a plurality of groups of trunk connecting devices available to said link switching system, each group comprising a plurality of trunk connecting devices, means in a trunk for actuating said link switching system, testing facilities in said link switching system arranged to simultaneously test the trunk connecting device of a group, an automatically operable switching device for successively and repeatedly switching said test facilities from one group of trunk connecting devices to another for successively and repeatedly testing the trunk connecting devices of said groups and for selecting an idle trunk connecting device in one of said groups, means in said testing facilities for arresting the action of said switching device when an idle trunk connecting device is selected, and means in said link switching system for connecting the selected trunk connecting device to said trunk.

3. In a telephone system, trunks, a link switching system, a plurality of groups of trunk connecting devices available to said link switching system, each group comprising a plurality of trunk connecting devices, means in a trunk for actuating said link switching system, testing facilities in said link switching system arranged to simultaneously test the trunk connecting devices of a group, a timing mechanism, an automatically operable switching device for successively and repeatedly switching said testing facilities from one group of trunk connecting devices to another for a time period regulated by said timing mechanism for successively and repeatedly testing the trunk connecting devices of said groups and for selecting an idle trunk connecting device in one of said groups, and means in said testing facilities for arresting the action of said switching device and said timing mechanism when an idle trunk connecting device is selected.

4. In a telephone system, trunk circuits, a link switching system including a plurality of switches and a plurality of selectable link control circuits, a plurality of senders in groups available to each of said plurality of link control circuits, means in a trunk circuit for actuating a link switching system causing the selection of an idle link control circuit, testing facilities in said control circuit for simultaneously testing the senders in a sender group, an automatically operable switching device in said control circuit for successively and repeatedly switching said testing facilities from one group of senders to another for successively and repeatedly testing the senders of said groups and for selecting an idle sender in one of said groups, and means in said testing facilities for arresting the action of said switching device when an idle sender is selected and for operating a link switch to connect the selected sender to said trunk circuit.

5. In a telephone system, trunk circuits, a link switching system including a plurality of switches and a plurality of selectable link control circuits, a plurality of senders in groups available to each of said plurality of link control circuits, means in a trunk circuit for actuating a link switching system causing the selection of an idle link con-

trol circuit, testing facilities in said control circuit for simultaneously testing the senders in a sender group, an automatically operable switching device in said control circuit for successively and repeatedly switching said testing facilities from one group of senders to another for successively and repeatedly testing the senders of said groups and for selecting an idle sender in one of said groups, means in said testing facilities for arresting the action of said switching device when an idle sender is selected and for operating a link switch to connect the selected sender to said trunk circuit, and a timing mechanism for arresting the action of said switching device when an idle sender is not selected within a predetermined time period and for disconnecting said control circuit from said trunk circuit.

6. In a telephone system, a trunk circuit, a link switching system including a plurality of switches and a plurality of selectable link control circuits, a plurality of senders in groups with a plurality of different groups available to each of said plurality of link control circuits, means in a trunk circuit for actuating a link switching system causing the selection of an idle link control circuit, testing facilities in said control circuit for simultaneously testing the senders in a sender group, an automatically operable switching device in said control circuit for successively and repeatedly switching said testing facilities from one group of senders to another for successively and repeatedly testing the senders of said groups and for selecting an idle sender in one of said groups, means in said testing facilities for arresting the action of said switching device when an idle sender is selected, a control circuit disconnecting relay, a timing mechanism for operating said relay to disconnect said link control circuit from said trunk circuit when no idle sender is selected within a predetermined time period and means in said link switching system responsive to the operation of said disconnecting relay for causing the selection of another link control circuit for successively and repeatedly searching other groups of senders to select an idle sender for connection to said trunk circuit.

7. In a telephone system, trunk circuits, a link switching system including a plurality of switches and a plurality of selectable link con-

trol circuits, a plurality of different character of senders in groups, like characters of senders being in the same group with a plurality of groups of each character of senders available for connection to any of said plurality of link control circuits for selecting idle senders for trunk connections, means in a trunk circuit for actuating a link switching system for causing the selection of an idle link control circuit, selective means in said control circuit for determining what character of senders shall be connected to said control circuit for selection, means in said trunk circuit for operating said character determining means, testing facilities in said control circuit for simultaneously testing the senders in a group of the character so determined, an automatically operable switching device for successively and repeatedly switching said testing facilities from one group of senders to another of the same character for successively and repeatedly testing the senders of said groups and for selecting an idle sender in one of said groups, and means in said control circuit for arresting the action of said switching device when an idle sender is selected.

8. In a telephone system, trunks, a link switching system, a plurality of groups of trunk connecting devices available to said link switching system, each group comprising a plurality of trunk connecting devices, means in a trunk for actuating said link switching system, testing facilities in said link switching system arranged to simultaneously test the trunk connecting devices of a group, an automatically operable switching device for successively and repeatedly switching said testing facilities from one group to another for successively and repeatedly testing the trunk connecting devices of said groups and for selecting an idle trunk connecting device in one of said groups, a timing mechanism for controlling the duration of time of switching said testing facilities from one group of senders to another for finding an idle trunk connecting device, a link switching system release circuit and means in said switch device controlled by said timing mechanism for switching said testing facilities to energize said release circuit during the test of the trunk connecting device in the last group having no idle trunk connecting devices therein.

ALOYSIUS J. BUSCH.
